UNITED STATES PATENT OFFICE.

HARRY E. MCCOY, OF PITTSBURGH, PENNSYLVANIA, ASSIGNOR TO THE McDOWELL MANUFACTURING COMPANY, OF MILLVALE, PENNSYLVANIA, A CORPORATION OF PENNSYLVANIA:

RACING TOY.

Application filed March 14, 1925. Serial No. 15,499.

This invention relates to toys or games, in which objects are caused to move in simulation or representation of racing figures.

The invention relates generally to toys of the same general type as those disclosed in my co-pending application Serial No. 690,264, filed February 2, 1924, and Serial No. 710,010, filed April 30, 1924, and also application Serial No. 15,500, filed the same day as this application.

In all of the said applications, a horizontal shaft is provided which has cranks thereon, on which cranks are the forward ends, such as the front legs, of racing objects, such as miniature toy horses. Means are provided for rotating the shaft, whereby a bobbing motion is imparted to the objects to give the effect of racing.

In the first of the above-named applications, the rotation of the shaft also causes it to revolve about a fixed center, so that the horses or other objects travel in a circle while they are bobbing up and down with the rotation of the shaft. In the second application above mentioned, the shaft is fixed in stationary supports, so that the racing objects merely bob up and down.

The present invention relates to the former type of toy, and has for its object to provide a novel racing toy, which is extremely simple to manufacture and wherein there is considerable "action."

The present invention has for a further object to provide a novel driving means for the shaft.

The invention may be readily understood by reference to the accompanying drawings, in which:

Fig. 1 is a plan view of a toy embodying my invention;

Fig. 2 is a side view from one position, showing the front of the racing objects, part of the flange of the base being broken away;

Fig. 3 is a similar view from a different position, showing the sides of the racing objects, and showing a side view of the movable stop.

In the drawings, 5 designates a plate or disk which preferably is provided with an upturned flange 6, so as to form a pan-shaped base for the toy. Suitably located on the disk, preferably at the center, is a fixed upright pin 7. Fitted over this pin is a sleeve 8 that is closed at its upper end and

to the lower end of which is secured a relatively heavy plate or disk 9, which may have a heavier hub portion 9^a. The pin and sleeve provide a spindle bearing for the plate having very little friction, so that by twisting knob 10 on the sleeve, the disk can be revolved, and rotate through its momentum for a considerable time.

Loosely fitted over the sleeve is a collar 11, the preferred form of which is illustrated, this collar having an upright 12 theron which carries a bearing 13 for the crank shaft hereinafter described. Depending from the collar is a bearing portion 14 and a pointer 15 diametrically opposite the bearing.

Having one end rotatably received in bearing 13 is a radially extending shaft 16 having a friction wheel 17 near its inner end, which also serves to support the inner end of the shaft and hold the pointer 15 above the hub 9^a of the rotating disk 9. The collar provides a pivoting anchorage for the shaft. On the outer end of the shaft is a wheel 18 that is beyond the periphery of disk 9 and accordingly rides on the bottom plate 5. Intermediate the two wheels, the shaft has one or more eccentrics or cranks 19 therein.

Rotatably engaging each crank or eccentric is the forward end of an object 20, such as a miniature representation of a horse, the front legs of the horse engaging the crank. The over-weighted rear end rests on the surface of the disk, so that only the front ends of the horses are elevated. When the disk 9 is rotated in the manner indicated, the shaft 16 is rotated through the engagement of friction wheel 17. If the disk rotates in the direction of the inner arrow in Fig. 1, the rotation of shaft 16 will cause wheel 18 to revolve the shaft 16 about the central sleeve in the direction of the outer arrow of Fig. 1.

Thus, the rotating shaft causes the horse to bob up and down, while the shaft, at the same time, travels in a circle about the center of the disk. Due to the fact that the disk on which the rear feet 20^a of the horses rest is traveling one direction while the bobbing horses are moving in the opposite direction, the appearance of considerable speed and consequently considerable action is obtained.

In order that a game may be played with the toys, a stop device may be provided to

control the number of times the horses travel around the circle. This device may include an upright 21 having a lateral foot 22 pivoted at 23 to the plate 5 and having a lateral handle 24 thereon. The flange 6 may be cut away at this point to provide clearance for the stop. The top of the post has a slightly inclined port 25 beyond the highest end of which is a notch 26 and lug 27. This notch 10 26 is so positioned that when the outer end of the shaft 16 is received therein, the wheel 18 will be slightly elevated, thereby permitting the shaft to rotate but preventing it from revolving.

15 In playing a game, the disk is revolved, with the stop in the position shown. Then the stop is swung to the dotted line position of Fig. 1, thereby freeing the shaft and letting the horses go forward. After one or 20 more revolutions, the stop may be swung back into shaft engaging position, the end of the shaft will climb incline 25 until the end of the shaft is again in the notch. The shaft may continue to rotate as thus engaged for a short time, and the horse whose head is furthest forward when the shaft 25 stops rotating is declared the winner.

Game points A may be pivoted on the hub portion of the disk, and the pointer 15 will 30 indicate one of these numbers when the disk has come to rest.

As thus arranged, a very attractive toy and game is provided, which has considerable action, and wherein there may be a definite stopping and starting point for the race.

While I have illustrated a preferred embodiment of the invention, it will be understood that various changes and modifications may be made therein within the contemplation of the invention and under the scope of the appended claims.

I claim as my invention:

1. A toy including a base, a horizontal shaft pivotally anchored at one end to the 45 base, a wheel at the outer end of the shaft, in contact with the base an eccentric on the shaft, a miniature racing object having one end only rotatably engaging the eccentric, whereby one end of such object is supported by the shaft while the other end is free to 50 travel on the surface below the shaft, and means for rotating the shaft.

2. A toy including a base, a horizontal shaft pivotally and rotatably anchored to 55 the base, a traveling support for the outer end of the shaft, a plurality of eccentric elements on the shaft, a racing object engaging each eccentric, and common means for rotating the shaft and propelling it to revolve about its pivot.

3. A toy including a base, a horizontal shaft pivotally and rotatably anchored to the base, a wheel at the outer end of the shaft normally resting on the base, a plurality of 65 eccentric elements on the shaft, a separate

racing object engaging and connected with each eccentric element, means for rotating the shaft to cause said objects to move up and down and to cause the shaft to revolve about its anchorage, and an abutment and support pivotally mounted on the base movable into and out of engagement with the outer end of the shaft for lifting the wheel off the base while permitting the shaft to rotate.

4. A toy including a base, a horizontal disk mounted for rotation above the base, a rotatable shaft above the disk having a pivotal anchorage at the center of the disk, a friction wheel on the shaft engaging the 80 disk for effecting rotation of the shaft upon rotation of the disk, a wheel at the outer end of the shaft normally engaging the base, a plurality of miniature racing objects having one end secured to the shaft and having their other ends resting on the disk, said shaft being caused to travel about its pivotal anchorage by rotation of the disk and in a direction opposite thereto.

5. A toy including a base, a horizontal disk mounted for rotation above the base, a rotatable shaft above the disk having a pivotal anchorage at the center of the disk, a friction wheel on the shaft engaging the disk for effecting rotation of the shaft upon rotation of the disk, a wheel at the outer end of the shaft normally engaging the base, a plurality of cranks on the shaft, a plurality of racing objects, each having a portion thereof connected with a crank and having a portion trailing on the disk, said objects being thus caused to bob up and down upon rotation of the shaft, rotation of the shaft causing said wheel to rotate to revolve the shaft about its pivotal anchorage.

6. A toy including a base, a horizontal disk mounted for rotation above the base, a rotatable shaft above the disk having a pivotal anchorage at the center of the disk, a friction wheel on the shaft engaging the disk for effecting rotation of the shaft upon rotation of the disk, a wheel at the outer end of the shaft normally engaging the base, a plurality of cranks on the shaft, a plurality of racing objects, each having a portion thereof connected with a crank and having a portion trailing on the disk, said objects being thus caused to bob up and down upon rotation of the shaft, rotation of the shaft causing said wheel to rotate to revolve the shaft about its pivotal anchorage, and an obstruction movably secured on the base having means thereon to engage the outer end of the shaft and movable into and out of shaft engaging position.

7. A toy comprising a base, a post on the base, a disk having a central stem rotatably fitted over the pin whereby it is revolvably mounted above the base, a collar surrounding the post, a horizontal shaft rotatably en-

gaging the collar, a friction wheel on the shaft engaging the disk, a wheel engaging the base supporting the outer end of the shaft, eccentrics on the shaft, and miniature 5 objects engaging the eccentrics and operated thereby.

8. A toy comprising a base, a post on the base, a disk having a central stem rotatably fitted over the pin whereby it is revolvably 10 mounted above the base, a collar surrounding the post, a horizontal shaft rotatably engaging the collar, a friction wheel on the shaft engaging the disk, a wheel engaging the base supporting the outer end of the shaft, eccentrics on the shaft, miniature 15 objects engaging the eccentrics and operated thereby, scoring characters on the disk, and a pointer on the collar opposite to which the scoring characters are successively moved 20 upon rotation of the disk.

9. In a toy, the combination with a base

having a pivot post, of a circular track, a horizontally extending shaft anchored to the base through the pivot post, an eccentric element on the shaft, a racing object engaging 25 the said element, a loosely mounted means on the post engaging the shaft at one end thereof, and means spaced from said post for supporting and rotating the shaft.

10. In a toy, the combination with a base, 30 of a circular track, means for rotatably mounting the track on the base, a horizontally extending shaft having an eccentric element on the shaft, a racing object engaging the said element, a wheel disposed near one 35 end of the shaft adapted to bear upon the track, and a shaft supporting wheel at the outer end of the shaft disposed on and adapted to travel on the base.

In testimony whereof I affix my signature. 40

HARRY E. McCOY.
